UNITED STATES PATENT OFFICE.

WILLIAM T. TAGGART, OF PLAINFIELD, NEW JERSEY.

FAUCET.

1,173,895.

Specification of Letters Patent. Patented Feb. 29, 1916.

Application filed April 17, 1915. Serial No. 22,009.

To all whom it may concern:

Be it known that I, WILLIAM T. TAGGART, a citizen of the United States, residing at Plainfield, in the county of Union and State of New Jersey, have invented certain new and useful Improvements in Faucets; and I do declare the following to be a full, clear, and exact description of the invention, such as will enable others skilled in the art to which it appertains to make and use the same.

This invention relates to improvements in faucets and more particularly to basin faucets.

15 The primary object of the invention is to provide a faucet which may be readily detached and replaced without the use of tools, by an unskilled person, thereby providing for the change of washers when they become 20 so worn as to cause leakage in the faucet.

Another object is to provide a faucet so connected with the coupling member that it may be quickly detached by imparting a one-quarter turn thereto, thereby especially 25 adapting it for use on basin faucets which are usually so close to the back of the basin that they cannot be unscrewed until disconnecting the faucet under the basin and taking it out.

30 Another object is to provide a simply constructed faucet of this character which may be removed without necessitating cutting off of the water.

With these and other objects in view, the 35 invention consists of certain novel features of construction, and the combination and arrangement of parts as will be more fully described and claimed.

In the accompanying drawings: Figure 1 40 represents a side elevation of a faucet and coupling constructed in accordance with this invention; Fig. 2 is a longitudinal central vertical section thereof showing the valves in closed position; Fig. 3 is a horizontal section taken substantially on the line 3—3 of Fig. 1 showing the valves in open position; Fig. 4 is a detail sectional view of the forward end of the coupling taken substantially on the line 4—4 of Fig. 7; Fig. 5 is a detail 45 rear elevation of the faucet; Fig. 6 is a transverse section taken on the line 6—6 of Fig. 4; Fig. 7 is a transverse section taken on the line 7—7 of Fig. 1; Fig. 8 is a similar view taken on the line 8—8 of Fig. 1.

50 In the embodiment illustrated, a tubular coupling 1 is shown for connecting the faucet 55

cet 2 with a water main not shown. This coupling 1 is exteriorly threaded at its rear end and is provided at its front end on the interior thereof with ratchet grooves 3 which have notches 4 opening through the front end of the member 1 to provide for the connection of the faucet with the coupling in a manner to be described. This coupling is also provided on its inner face at a point about midway its ends with an annular threaded portion 5 having a shoulder 6 at the front end thereof with which one end of a tubular nipple 7 is arranged flush when mounted in said coupling. This nipple 7 is in the form of an exteriorly threaded sleeve designed for threaded engagement with the threaded portion 5 of the coupling, and the rear end of which is contracted and reduced to adapt it to form a seat for a valve 9 hereinafter to be described. This nipple 7 is shown provided on its inner face with a plurality of pairs of oppositely disposed longitudinally extending grooves 7' which are designed to receive a screw driver for 80 positioning the nipple and engaging it with the threaded portion 5 of the coupling. The coupling 1 at the rear of the nipple 7 is provided with longitudinally extending corrugations 8 which provide for the passage 85 of the water between the sides of said nipple and of a valve 9 which is slidably mounted in said coupling between the nipple 7 and the rear end thereof, said coupling being provided with laterally extending stops 10 to limit the rearward movement of said valve. This valve 9 is shown in the form of a cylindrical block having its rear end truncated cone-shaped as shown at 11 to receive the impact of the inflowing water and against which the water under pressure impinges and forces the valve forward into close engagement with the nipple 7, thereby cutting off the supply of water through said coupling, it being understood that the water pressure in the main will normally hold this valve in closed position, and that when the valve is opened, the water will flow freely between the side walls thereof and the grooves in the coupling member and pass through said nipple to the faucet connected to the front end of the coupling 1. The front end of this valve 9 has a concave seat 12 which is designed to receive an operating member hereinafter to be described.

110 The faucet 2 is provided at its inner or rear end with a tubular extension 13 having

an annular flange or shoulder 14 spaced inwardly from its free end and which forms a limiting stop for the insertion of said extension in the tubular coupling 1 and 5 against which the front end of said coupling abuts when the parts are in assembled position. This tubular extension 13 is provided on its periphery intermediately the length thereof with a plurality of laterally projecting lugs 15 arranged in circumferential alinement and which are designed to enter the notches 4 of the coupling 1, and on giving the faucet a quarter turn, said lugs become locked with the walls of the ratchet grooves in said tubular coupling, three of 10 said notches and grooves being shown in the coupling and three lugs on the faucet. These grooves as illustrated are inclined downwardly and inwardly from their communicating notch to a point adjacent the next succeeding notch. By so forming these parts it will be obvious that a quarter turn 20 only of the faucet is necessary for either coupling or uncoupling it with the member 1, and this attachment is especially applicable to basin faucets for the reason above set forth.

This faucet 2 is of ordinary construction, being provided with a cone-shaped valve 20 30 having a rubber washer 16 encircling it, and which is held in place by a threaded cap 17 having wings 17' to provide for its ready application and removal when it is desired to change the washers. This valve 20 is 35 mounted on a stem 18, the front end of which has an eye 19 to receive an offset extension 21 formed on the inner end of the valve opening shank or stem 22 which extends laterally through one wall of the faucet and is provided with the usual handle 23.

The stem 18 of the valve 20 projects beyond the rear end thereof and is designed to pass into the tubular coupling 1 and the nipple 7 with its free end positioned in the 45 concave seat 12 of valve 9 whereby it is centered, and on the turning of the handle 23 in the direction for opening said valve 9 so that when said valve 20 is opened, the stem thereof will forcibly engage the valve 50 9 and press it backward into the tubular coupling member away from its seat on the nipple 7 and thus permit the water to flow freely through the faucet.

When it is desired to cut off the water, 55 the handle 23 is turned in the opposite direction, thereby drawing the washer covered valve 20 in close engagement with the seat

at the end of the faucet and thereby cutting off the water from the faucet. This closing of the valve 20 withdraws the stem 18 60 thereof from engagement with the valve 9, which under the pressure of the water in the main would automatically seat on the nipple 7 and thus insure the complete cutting off of the water from the faucet. The 65 water pressure will hold this valve 9 in closed position until again actuated in the manner above set forth, and consequently will permit the faucet being detached from the coupling 1 without any leakage or discharge of water from the coupling. 70

Another advantage resulting from the use of this improved faucet is that it may be used as a draw-off cock on hot water boilers so that when it is desired to change the 75 washers thereon it will not be necessary to empty the whole system or boiler, the faucet being readily detachable without cutting off the water in the manner above described.

I claim as my invention:

In a faucet, a tubular coupling having the bore thereof larger at one end than at the other with an annular shoulder formed at the junction of said larger and smaller portions, the smaller portion being threaded 80 adjacent said shoulder, longitudinal corrugations formed on the inner face of the reduced portion of said bore and extending from said threaded portion rearwardly, a 85 nipple engaged with said threaded portion and having a rearwardly projecting exteriorly reduced extension, a cylindrical valve 90 slidable in the corrugated portion of said bore and having a truncated cone shaped rear end and a concaved inner end for receiving said nipple extension whereby a watertight connection is normally formed 95 between them and which are so held by the impact of the inflowing water against the cone shaped end of said valve, a valve opening member extending through said nipple and entering said concaved valve end, and means for forcing said member rearwardly 100 against said valve whereby the valve is opened against the pressure of the inflowing water. 105

In testimony whereof I have hereunto set my hand in presence of two subscribing witnesses.

WILLIAM T. TAGGART.
